UNITED STATES PATENT OFFICE.

EMIL HERMAN ZUM BERGE, OF DALLAS, TEXAS.

LIFTING-JACK.

No. 882,991.

Specification of Letters Patent. Patented March 24, 1908.

Application filed October 4, 1907. Serial No. 395,856.

To all whom it may concern:

Be it known that I, EMIL HERMAN ZUM BERGE, a citizen of the United States, and a resident of Dallas, in the county of Dallas 5 and State of Texas, have invented a new and Improved Lifting-Jack, of which the following is a full, clear, and exact description.

This invention relates to lifting jacks and 10 is particularly useful for lifting car trucks to permit the removal of journal bearings.

An object of the invention is to provide a simple, strong and efficient lifting jack, by means of which the journal of a car truck can 15 be easily and rapidly lifted while the wheel remains upon the track, to permit the removal of the brasses, and which can be operated expeditiously and with the application of little power.

20 A further object of the invention is to provide a device of the class described, in the use of which the car wheel is employed as a support, and which operates in such a manner that the journal is raised while the car wheel 25 remains upon the track rail, a cam member having means for its manual operation serving to elevate the journal by engaging the journal box.

The invention consists in the construction 30 and combination of parts to be more fully described hereinafter and particularly set forth in the claims.

Reference is to be had to the accompanying drawings forming a part of this specification, 35 in which similar characters of reference indicate corresponding parts in all the views, and in which

Figure 1 is a side elevation of one end of a car-truck showing my device applied thereto; 40 Fig. 2 is an end view of the car-truck showing parts in cross-section; Fig. 3 is a view similar to Fig. 2 showing parts in different positions; Fig. 4 is a plan view of a detail; and Fig. 5 is an elevation of a detail of modified form.

45 Before proceeding to a more detailed explanation of my invention, it should be understood that the same can be used for a variety of purposes to which lifting jacks are usually put, though it is particularly useful in lifting 50 the journal or axle boxes of railway cars, when it is desired to remove or replace the brasses thereof.

It has been found in practice, that in elevating car trucks for the purposes mentioned 55 above, the raising of the journal box often causes the wheel adjacent to the journal box

to move upwardly, unless it is blocked to prevent this movement. The upward movement of the wheel will cause the car to tilt toward the side opposite that upon which 60 the journal box is disposed, unless the wheel is suitably blocked to hold it against such movement. It is inconvenient and a source of loss of time and labor, properly to block the wheel, and my invention is particularly 65 useful as it prevents the rising of the wheel, as the latter is used for a support, and in the operation of the lifting jack is therefore subject to a downward pull.

Referring more particularly to the drawings, 1 represents a car truck of conventional design, one end only of which is shown in the illustration. The truck carries a journal box 2 which is provided with the usual brass 3 which rests upon the journal 4 of the wheel 5. 75 It will be understood that the weight carried by each journal is supported by the same through the brass of the journal box, the brass resting upon the upper surface of the journal as is shown most clearly in Fig. 1. 80 Consequently, when the brass is to be removed, it is necessary to raise the journal box from the journal to permit the brass which is jammed between the two, to be withdrawn. I provide a hook or support 6, formed from 85 suitable material such as iron or steel, and having at one end a hook portion 7 adapted to extend over the flange 8 of the wheel and to engage at the under side of the wheel rim, the shank of the hook extending outwardly 90 beyond the wheel and being provided with notches 9. A yoke bar 10 is removably located in one of the notches 9, and at the end has transverse sleeves 11 in which are mounted depending hanger rods 12. The upper ends 95 of the hanger rods are threaded and extend upwardly beyond the sleeves 11, being held in position by means of nuts 13. At the lower ends of the hanger rods are formed eyes or bearings 14 which carry a rotatable, 100 transverse shaft 15.

Rigidly mounted upon the shaft 15 is a cam member 16, preferably cylindrical in form and arranged eccentrically with respect to the shaft. The cam member, which, 105 together with the shaft is rotatable, has formed therein peripheral openings 17, adapted to receive the end of a hand bar 18, by means of which the rotatable member can be operated. At one end, the cam member 110 is provided with a ratchet 19. A shoe 20, having the under side curved so that the shoe

seats evenly upon the cam member, is removably mounted between the same and the bottom of the journal box when my device is in operation. Near the forward end, the 5 shoe 20 has an upward projection 21 arranged to engage at the front of the journal box, while at the rear are laterally disposed toes 22, which extend behind the truck bolts 23 and serve thereby to hold the shoe in position. 10 Toes 24 extending laterally near the front of the shoe 20 serve a similar purpose. At one side, the shoe 20 has a pivotally mounted dog 25, which is arranged to engage with the teeth of the ratchet 19 and thus prevent the 15 movement of the rotatable member in one direction.

In using my lifting jack, the supporting member 6 is placed in position as described above, and the yoke bar 10 on the supporting 20 member in one of the notches 9. The rotatable member is located underneath the journal box and carries the shoe which engages at the under side of the journal box.

25 Before operating the device the parts can be suitably adjusted by means of the nuts on the hanger rods. The eccentric member is then rotated by means of the hand bar 18, and as it revolves the throw of the eccentric 30 forces the shoe upward and this carries with it the journal box, thereby raising the latter above the journal and freeing the brasses so that the latter can be easily removed. It will be understood that as the rotatable 35 member is operated, the hand bar can be removed from one of the openings 17 and placed in another, as is most convenient to the operation. The dog 25 holds the cam against a reverse movement when the hand 40 bar is released. When it is desired to lower the journal, it is merely necessary to withdraw the dog and the weight supported by the shoe will return the device to its original position.

45 In Fig. 5 is shown a hook or support 6 of modified form. In this modification the support is extended in a substantially horizontal direction beyond its engagement with the car wheel 5 and at the end has a pivotally 50 mounted hook 6^a which carries the yoke bar 10. With this form of the device the same is applicable to car trucks of different types and car wheels of different sizes.

Having thus described my invention, I 55 claim as new and desire to secure by Letters Patent:—

1. In a device of the class described, in combination, a support adapted to engage a car wheel and carrying a hanger, a member 60 mounted upon said hanger, and rotatable about a substantially horizontal axis elevating means controlled by said member and adapted operatively to engage a journal box and means for preventing the movement of said member in one direction.

2. In a device of the class described, in combination, a support adapted to engage a car wheel and carrying a hanger, a rotatable member mounted upon said hanger and adapted to be manually operated, a shoe 70 adapted to engage said member and a journal box and to be moved by said member, and means for preventing the movement of said member in one direction, said member being rotatable about an axis substantially at right 75 angles to the direction of movement of said shoe.

3. In a device of the class described, in combination, a support adapted to engage a car wheel and carrying a hanger, a rotatable 80 member mounted upon said hanger and having a cam, and means for operating said member to rotate said cam, said cam being arranged operatively to engage a journal box, said member being rotatable about an axis 85 substantially at right angles to the direction of the movement of the journal box effected by said cam.

4. In a device of the class described, in combination, a support adapted to engage a car wheel and carrying an adjustable hanger, a rotatable member mounted upon said hanger and having a cam adapted operatively to control a journal box, means for 90 manually operating said rotatable member, and means for preventing the movement of said member in one direction, said member being rotatable about a substantially horizontal 95 axis.

5. In a device of the class described, in combination, a support adapted to engage a car wheel and carrying a removable hanger, said hanger being adjustable, a rotatable member mounted upon said hanger and adapted to be manually operated, said rotatable member including a cam, a shoe 100 removably arranged upon said cam and adapted to engage a journal box, and means for preventing the movement of said member in one direction.

6. In a device of the class described, in combination, a support adapted to engage a car wheel and removably carrying a hanger, said hanger being adjustable, a rotatable member mounted upon said hanger and having means for its manual operation, said rotatable member having a cam, a shoe 105 removably mounted upon said cam and adapted to engage at the under side of a journal box, and means carried by said cam for preventing the movement of said member in one direction.

7. In a device of the class described, in combination, a support adapted to engage at the rim of a car wheel and extending beyond 115 the wheel at the opposite side, a hanger comprising a yoke adapted to be removably held by said support and provided with adjustable hanger bars, a shaft movably carried by said hanger bars and having rigid therewith a 120 125

130

cam, said cam having means for its manual operation, a shoe adapted to be removably carried by said cam and to engage at the under side of a journal box, said shoe having 5 projections serving to hold it in position, a ratchet rigid with said cam, and a dog carried by said shoe and adapted operatively to engage said ratchet.

In testimony whereof I have signed my name to this specification in the presence of 10 two subscribing witnesses.

EMIL HERMAN ZUM BERGE.
